UNITED STATES PATENT OFFICE

OLIVER P. GREENSTREET, OF OWENSVILLE, MISSOURI

ANTIFREEZE COMPOUND FOR RADIATORS

No Drawing.

Application filed June 25, 1931. Serial No. 546,925.

This invention relates to anti-freezing compounds adapted to be used in the radiators of automobiles in place of alcohol, glycerine or other anti-freeze mixtures now on the market.

In previous applications made by me, (Serial No. 447,087, filed April 24, 1930 on anti-freezing liquid and Serial No. 479,805, filed September 4, 1930 on anti-freezing liquid,) I described an anti-freezing liquid which consisted of kerosene, from which the lighter and more volatile fractions had been eliminated to thus raise the flash point of the kerosene, with which kerosene oil of mirbane had been mixed for the purpose of preventing the kerosene from boiling, the oil of mirbane acting to render the boiling point of the kerosene very high or approximately 322° F.

The mixture of kerosene from which the lighter fractions had been removed and oil of mirbane constituted a very effective anti-freeze liquid to be placed in radiators but if there was any water left in the radiator when this mixture was placed therein, the water would not mix with the kerosene and oil of mirbane and this water flowing over the hot engine head would readily boil. Also this water would freeze on cold days.

While it was designed that every bit of water should be drawn from the radiator, in the majority of cases, some water was left which resulted in the above named conditions.

It was necessary then to provide means whereby any water left in the radiator should mix with the kerosene and oil of mirbane. To that end, it was necessary to provide an emulsifier causing the oil of mirbane and kerosene to absorb some water and causing any excess water to mix with the oil of mirbane and kerosene while the engine was running. However, this would not prevent any excess water from freezing when the engine was stopped on a cold day. It was, therefore, necessary to add glycerine to the emulsifier. Glycerine would mix with the excess water, but not with the kerosene and oil of mirbane.

There is still another difficulty, however,

found in the use of this anti-freezing compound, namely leakage. The kerosene and oil of mirbane cuts rust and corrosion and when the compound is used in old cars, especially when the rust is cut loose, a leak would appear. Therefore, it is necessary to add an anti-leak powder to prevent this.

The present invention has for its object, therefore, the production of a compound which may be either initially mixed with kerosene and oil of mirbane or which may be added to kerosene by the car operator, thus permitting kerosene to be used in a radiator even though all of the water has not been drained out of the radiator and producing when so added an anti-freeze mixture having a very high boiling point which will not freeze except at excessively low temperatures, which will cause an emulsification of any water remaining in the radiator, which will prevent this water from freezing, and which will stop any leaks caused by the action of the kerosene in cutting the rust and corrosion, this mixture furthermore lessening the solvent effect of the mixture on rubber.

In initially preparing a complete anti-freeze liquid, I use petroleum in the form of coal oil or kerosene to which is added oil of mirbane (mono-nitro-benzine, $C_6H_5NO_2$), the kerosene being heated to eliminate the lighter and more volatile fractions and thus raise the flash point of the kerosene. In other words, I boil away the lower fractions of the kerosene and use the higher boiling kerosene fraction. By adding the proper quantity of oil of mirbane, I can raise or lower the boiling and freezing range of the liquid and preferably I use a mixture that will not freeze until -43° F. has been reached and which cannot boil until 322° F. has been reached.

While I do not wish to be limited to any particular proportion of the oil of mirbane relative to the kerosene, I preferably use one part of oil of mirbane to sixty-four parts of kerosene.

After preparing the mixture of oil of mirbane and kerosene, I add to this mixture an emulsifier. Preferably as an emulsifier, I

use sulphonated bitumen. Preferably, I will use one part of sulphonated bitumen to sixty-four parts of kerosene. With this is mixed glycerine, flax seed and zinc oxide. The 5 zinc oxide and flax seed are used as a leak stopper, the ground flax seed acting as a carrier of the zinc oxide.

While I have heretofore described the mixing of oil of mirbane, the emulsifier, flax 10 seed and zinc oxide together to form a complete anti-freezing compound, I do not wish to be limited to these steps inasmuch as I contemplate the production of what may be termed a partial anti-freezing compound 15 which may be added to kerosene by the car operator himself.

Under these circumstances, the following compound is used, namely:—sulphonated bitumen, as an emulsifier, six ounces, glycerine, three ounces, oil of mirbane six ounces, flax seed, one-half ounce, and zinc oxide, one-half ounce. These several ingredients are mixed together and put up in a can or tube and preferably in the form of a paste. This 20 mixture is to be added to a radiator that is filled with kerosene. Sixteen ounces of this paste or semi-liquid will take care of three gallons of kerosene.

It is to be understood, of course, that 30 these proportions might be changed at least within the following range, of proportions, namely:—

Oil of mirbane _____ Four to eight ounces
35 Sulphonated bitumen _____ Four to eight ounces
Glycerine _____ Two to four ounces
Flax seed _____ One-quarter to one ounce
Zinc oxide _____ One-quarter to one ounce

It will be understood that the sulphonated 40 bitumen acts as an emulsifier to emulsify any water which may remain in the radiator, that the glycerine prevents any water from freezing, that the oil of mirbane very greatly increases the boiling range of kerosene, 45 that the flax seed acts as a carrier for the zinc oxide. The flax seed will readily circulate with the oil of mirbane and kerosene when the motor is started and carries the zinc oxide to the leak and holds it there until 50 the zinc oxide becomes hard on the outside of the leak. The zinc oxide becomes hard when the air hits it, but it remains soft in the liquid itself. This mixture has been carefully tested and is entirely satisfactory.

55 While this mixture will ordinarily be put up in the form of paste, yet it may be rendered liquid by adding thereto a little kerosene. I reiterate that this mixture of sulphonated bitumen, oil of mirbane, glycerine, 60 zinc oxide and flax seed may be put up separately for use with kerosene or that the combination of kerosene, oil of mirbane, glycerine, the emulsifier, flax seed and zinc oxide may be put up for sale as a complete anti-freezing mixture.

It will be understood that this mixture through the absorption and mixing of water with the complete mixture, the disturbance caused by the presence of the water, under heat, does not begin until the temperature arrives at 212° F., whereas if there was no emulsifying agent, such as sulphonated bitumen, there would be a disturbance at 180° F. It is very essential that this point of disturbance caused by the presence of water be raised from 180° to 212° in order that the motor may function properly with this mixture as a cooling agent.

I claim:—

1. An anti-freezing mixture consisting approximately of kerosene three gallons, oil of mirbane six ounces, sulphonated bitumen six ounces, glycerine three ounces, flax seed one-half ounce, and zinc oxide one-half ounce.

2. A compound of the character described, consisting of sulphonated bitumen four to eight ounces, glycerine two to four ounces, oil of mirbane four to eight ounces, flax seed one quarter to one ounce, and zinc oxide one quarter to one ounce.

3. An anti-freezing mixture consisting of kerosene three gallons, oil of mirbane from four to eight ounces, sulphonated bitumen from four to eight ounces, glycerine from two to four ounces, flax seed from one quarter of an ounce to one ounce and zinc oxide from one quarter to one ounce.

4. An anti-freezing mixture for use in radiators of automobiles comprising kerosene from which the higher boiling point fractions have been eliminated, oil of mirbane and an emulsifier of a character to emulsify water with oil such as sulphonated bitumen or its equivalent.

5. An anti-freezing mixture for use in radiators of automobiles comprising kerosene from which the higher boiling point fractions have been eliminated, oil of mirbane, an emulsifier of a character to emulsify water with oil such as sulphonated bitumen or its equivalent, and a leak stopper consisting of a mixture of flax seed and oxide of zinc.

6. A compound of the character described, consisting of oil of mirbane, four to eight ounces, sulphonated bitumen or its equivalent from four to eight ounces, glycerine, from two to four ounces, flax seed from one-quarter to one ounce, and zinc oxide from one-quarter to one ounce.

In testimony whereof I hereunto affix my signature.

OLIVER P. GREENSTREET.
